TURF CULTIVATOR

Frank R. Donoho and Charles C. Bennett,
Asheville, N. C.

Application April 15, 1939, Serial No. 268,080

5 Claims. (Cl. 111—1)

This is a continuation-in-part of application Serial Number 220,995, filed July 23, 1938.

This invention relates to a method of and apparatus for cultivating turf and the like and more particularly to such a method and apparatus adaptable for use in connection with the care of golf greens involving the loosening of the soil underlying the turf without even a temporary impairment of the playing surface.

In the maintenance of golf greens the art has long been faced with the problem of the cultivation of the turf without impairment of the playing surface. During recent years this problem has become more acute due to the increasing popularity of golf with the resultant crowding of the links and packing of the soil underlying the turf. Then, too, there has developed an increasingly critical attitude on the part of the players with respect to the condition of the greens. Thus, well maintained greens are required and in many localities the problem of providing satisfactory greens is exaggerated by the prevailing practice of playing golf throughout the entire year.

Heretofore various practices have been resorted to for maintaining the turf in the condition desired. One of these practices contemplates the provision of alternate greens, so that one green may be cultivated during a period while the other is being used. Such an expedient, however, involves the additional expense in the preparation and maintenance of the alternative greens and at times it causes inconvenience to the players.

A more common practice heretofore utilized to maintain the greens in the desired condition involves the practice of scarifying. In the scarifying treatment the greens are pierced at closely spaced points and the holes so formed are so minute as not to impair the playing surfaces. To cultivate the turf by the scarifying method, rollers provided with numerous short projections on the surface thereof have been utilized. The scarifying practice has also been conducted by the utilization of an apparatus having flat discs the edges of which cut very fine lines in the surface of the green and in this way provide some measure of cultivation. However, it will be clear that treatments which involve a cultivation, merely coextensive in area with the area pierced, will either deleteriously affect the playing surface or provide only a negligible cultivation.

Still another procedure which has been utilized in the maintenance of golf greens and the

like involves the complete removal of the sod, the conditioning of the exposed ground, and replacement of the sod together with reseeding.

Incident to the maintenance of the turf it is at times necessary to supply suitable fertilizer thereto. Heretofore the application of fertilizer has been by the distribution of the same on the surface, reliance being placed on surface water to conduct the same to the roots of the turf. Such practice interferes with the playing surface and is quite inefficient because much of the fertilizer is wasted. This deficiency in the application of fertilizer as suggested has been recognized in the art and attempts have been made to supply the fertilizer to the roots in a more efficient manner. Among the methods utilized to improve upon the usual surface fertilization procedure is that which involves the application of fertilizer upon a scarified surface. It is clear that but slight improvement in application of fertilizer is had by the use of the minute openings made through the turf.

It is an object of the present invention to provide an apparatus for cultivating turf such as that of golf greens and the like in which practical means are had for effectively working the soil over a large area below the turf so that large scale cultivation may be effected without disturbing or impairing the turf so treated.

It is also contemplated by this invention to cultivate the turf, including where desirable the application of fertilizer, in a manner which involves the working of the soil immediately below the turf while only spaced slits are made therethrough, which slits are closed immediately following the working of the soil leaving the surface unimpaired.

Additionally this invention has as an object the provision of a cultivator for turf involving a member adaptable for working a wide swath of soil immediately beneath the turf, said member being operable through a very narrow slit cut through the turf and containing means for broadcasting fertilizer over an area coextensive with the worked area.

The method which is more specifically contemplated by this invention includes the working or pulverizing of the soil below the turf throughout a large area to permit better retention of moisture within the soil and to produce the desired amount of ventilation to give the roots room for growth and development. Furthermore, the application of a predetermined amount of fertilizer to the ground being worked, together with subsequent treatment of soil under

adjacent turf while maintaining the surface of the turf in substantially unchanged condition thereby to permit the proper maintenance of the turf without substantial interruptions in the use thereof is contemplated.

Other objects and advantages of the present invention will be apparent from a consideration of the following detailed description when taken in conjunction with the accompanying drawings wherein:

Figure 1 is a view in side elevation of a preferred form of the invention shown in operative position;

Figure 2 is a plan view of a cultivator formed in accordance with this invention;

Figure 3 is a view of the machine shown in Figure 2 in side elevation illustrating the position assumed thereby during transportation or storage;

Figure 4 is a sectional view taken along the line 4—4 of Figure 2;

Figure 5 is a detail view of the plow member of the machine showing means for vertically adjusting the same;

Figure 6 is a bottom plan view of the plow member;

Figure 7 is a detail view of the fertilizer distributor;

Figure 8 is a detail view of the clevis of the machine of Figure 1 shown in latched position; and

Figure 9 is a detail view of the clevis of the machine of Figure 1 shown in unlatched position.

Now in referring to the drawings in detail, the numeral 10 designates a frame which is formed of two sections 11. Secured between the sections 11 at the forward end of the frame 10 is a composite roller 12 having two sections 13 and 14 and a circular blade 15 clamped therebetween. Sections 13 and 14 and blade 15 are keyed to a shaft 16 which is journaled in the respective frame sections 11.

Arranged rearwardly of the roller 12 and supported by the frame is a plow and fertilizer assembly 17. The plow and fertilizer assembly includes a hopper 18 having a sloping lower wall 19 in the form of a truncated cone. At the point where lower wall 19 is truncated there is provided a screened eccentrically arranged opening 20 of adjustable size through which fertilizer or other soil treating material is adapted to be discharged. A shaft 21 provided with arms 22 and 23 is centrally arranged within the hopper 18 having its lower end suitably journaled at 24 and extending below the hopper 18. Radial vanes 25 are keyed to the shaft 21 and rotate therewith for the purpose of discharging the powder from housing 26 in which the radial vanes are contained. A bearing 27 in which is journaled a laterally extending shaft 28 is mounted upon the lower portion of the hopper and this shaft has provided on the inner end thereof a bevel gear 29 which meshes with a bevel gear 30 keyed upon shaft 21.

The plow and fertilizer distributor assembly 17 is also provided with a plow shank 31 which is in alignment with circular blade 15 and acts as a wedge in the turf and carries on its lower end a space forming member 32 in the shape of a flat plate having an arcuate trailing end 33 and a sharpened forward edge 34. The flat plate 32 has secured thereto a diverging plate 35 of generally rectangular configuration. Plate 32 is arranged at an angle to the plow shank with its

rear end 33 elevated, whereas plate 35 which is rigidly secured to the underside of plate 32 is perpendicularly disposed with respect to the plow shank. Teeth 36 are secured to the underside 5 of the plow arranged laterally in an angular formation with the centermost tooth being the most advanced (see Fig. 6). A tube 37 is secured in an opening 38 in plate 32 and extends upwardly adjacent the plow shank to a point immediately below the discharge opening of the fertilizer hopper. Tube 37 is provided at its upper end with a flared inlet into which the discharge member 39 is partially telescoped.

On front roller shaft 16 is a sprocket 40 having chain 41 engaging the same and connecting it with sprocket 42 keyed to shaft 28. Due to this construction, the rotation of roller 12, as the machine is moved over the ground during operation, causes the discharge of the fertilizer from the hopper in the manner previously indicated. A large pulley 43 is keyed to shaft 28 inwardly of sprocket 42. Support 44 is mounted at the forward end of frame 10 and has secured thereto a case 45 for the flexible shaft 46 where the latter is keyed to shaft 47 on which pulley 48 is mounted. A belt 49 is passed over pulley 43 and thence over pulley 48 which is driven at a very high speed, although roller 12 from which it derives its motion is normally operated at a low speed. Flexible shaft 46 extends downwardly through tube 37 and carries at its lower end a rotor 50 provided with radially extending vanes 51, and since this rotor will be operated at a very high speed it will cause the violent broadcasting of fertilizer as it is discharged from the tube 37 above the rotor 50.

Hopper 18 is rigidly secured in a fixed position upon the frame 10 by a bracket 52 and the plow and plow shank are adapted to be moved relative thereto, thereby to control the depth at which the plow operates within the soil, the telescoping arrangement of the flared portion of the tube 37 and discharge outlet 39 of the hopper permitting this adjustment without effecting a sufficient separation of the members to cause the loss of fertilizer therebetween. The plow and plow shank are adjusted through the medium of a clamping bolt 53 riding in the slot 54 arranged in the plow shank.

The rear end of the machine is maintained properly spaced from the surface of the ground by means of a roller 55 mounted upon an axle 56 secured in the frame 10 at 57.

For the purpose of propelling the machine in operation a clevis 58 is secured between the frame sections at the forward end thereof and a rope or cable 59 is utilized to connect the clevis 58 to a draft device 60. Between the machine and the draft device, rope 59 is passed through a ring 61 on guide post 62 so that the operator may view the rope and determine the course to be followed.

The clevis 58, which is illustrated in detail in Figures 8 and 9, consists of a perforated plate 63 which is bolted to frame sections 11, being received between the free ends thereof. The perforations 65 in plate 63 are vertically arranged and are adapted to receive a bolt 64 which is passed through the rear end of a pair of coupling plates 66 and through the selected one of the perforations 65 in the perforated plate 63. Coupling plates 66 are recessed at their forward ends to receive the pin 67 of a U-shaped yoke 68 and they have pivoted thereto a hasp 69 which is provided with a short extension 70 for under-

lying the pin 61 of the yoke 68 when the latter is in its operative position. Hasp 69 is maintained in the operative position by means of a latch 71 which latch is pivoted between the coupling plates 66 and is recessed at 72 above its pivot pin 73 for the reception of the end of the hasp 69; and latch 71 is maintained in the locked position by means of a coil spring 74 and a stop member 75 is arranged between the coupling members 66 to cooperate with dog 76 on latch 71 whereby the latch member will be held in position for easy coupling. A rope or cable 77 is secured to the free end of an upward extension provided on the latch member 71 and this cable is normally maintained over a cross-bar 78 which connects handles 79 which are in turn secured to the frame sections 11 adjacent the rear portion thereof. The hook 80 is provided as a separate handle for the convenience of the operator in actuating the latch 71 through rope 77.

When it is desired to move the machine about in a position such that the blades 36 will not contact the earth, roller 81 is employed. This roller is attached to depending ends of the portion of the frame 10 to which the plow shank 31 is connected through shaft 82 to which crank lever 83 is keyed. Pivotal mounting on the frame is provided at the point where shaft 82 is located so that the roller may be moved about that point 30 as an axis into the positions of Figure 1 and Figure 3. In order to pivot the roller 81 about its pivot point, levers are provided for actuating the crank lever 83. To this end a handle 84 is provided attached to link 85 which is pivotally attached at 86 to an upwardly extending arm of bracket 87 permanently secured to cross-bar 88 connecting the handles 79. The handle 84 is pivotally connected to link 89 which is in turn pivotally connected to the crank lever 83 at 90.

The operation of the device is as follows. The machine is towed while in the position shown in Figure 3 to the situs of the turf cultivation to be accomplished. The ground is then suitably marked off with guide sticks 62 which are necessary so that the operator may distinguish that portion of the turf which has been cultivated from that which has not. A draft attachment is made through ring 61 in the guide post 62 between draft equipment and the clevis 58. The device is then placed in the position shown in Figure 1 by the movement of handle 84 upwardly to pivot link 85 about its axis at 86. This will function to increase the effective length of link 89 by twice the length of link 85. Since link 89 is pivoted to crank lever 83 at 90, the forward movement of link 89 will cause the crank lever 83 to move about its axis at 82 lifting the roller 81 to the position shown in Figure 1. Because of the position of the fulcrum 82 there will be a considerable mechanical advantage in the operation of the lever 83 so that the roller 81 may be very easily moved and it will be retained in raised position by the bracket 87 which will keep links 85 and 89 generally straight. Because of the shape of the member 32 the teeth 36 will be quickly drawn under the surface to a depth determined by the adjustment of the bolt 53 in the slot 54 in shank 31. At this time, the device will be in the position shown in Figure 1. As it is pulled along it will be apparent that rollers 12 and 13 will contact the surface of the turf and that disc 15 will cut through the turf an amount equivalent to the difference between its radius and that of rollers 12. The cut so provided may

be very narrow but will be sufficient to accommodate the shank 31 which shank acts as a wedge for the plow 17 in such a manner as to avoid tearing of the turf. Beneath the ground, teeth 5 on the extending portions 32 and 35 of the shank 31 will loosen the soil laterally of the cut made by the disc 15 through which said shank passes. As the ground is being worked by the teeth 36, the rotation of shaft 16 through contact of rollers 12 with the turf, will actuate the shaft 28 through chain 41 to drive the fertilizer dispensing mechanism in the fertilizer container 18. The rotation of the vanes 25 will be directly proportional to the speed of the device so that the amount of fertilizer dispensed will be proportional to the area of ground covered. The fertilizer is dispensed in predetermined amounts through adjustable opening 20 leading into housing 26 from whence it will pass into tube 37 leading into the chamber defined intermediate the members 32 and 35 where it will be broadcast by the very rapid rotation of rotor 50 driven through flexible shaft 46 from the pulley 48 by virtue of the belt connection 49 to the large pulley 43. It will be apparent that the rotor 50 will be driven at a speed far greater than the dispensing vanes 25 in housing 26 so that the broadcast fertilizer will cover an area substantially coextensive with the pulverized area.

As the ground is being suitably agitated by the teeth 36 and fertilized through the action of broadcasting device 50 the seam made by the disc 15 is progressively closed by roller 55, thus leaving the surface of the turf substantially the same as prior to the cultivation. In view of the fact that the seam is so effectively closed by the roller 55, it is difficult for the operator to determine what area has been covered. Consequently stakes 62 are spaced apart a distance generally commensurate to the width of member 32 so that the area to be cultivated may be worked without leaving small uncultivated portions.

In the event an obstruction is encountered by the teeth 36 it is only necessary to pull rope 77 to release the clevis 58 as shown in Figure 9.

The device is brought again to the position shown in Figure 3 by movement of the handle 84 rearwardly to shorten the effective length of link 89 thus pivoting the roller 81 about the pivot point of shaft 82 until it reaches the operative position.

Although the above description has reference to a specific embodiment of the invention, it will be apparent that many modifications thereof are possible. The invention, therefore, is not to be restricted except insofar as is necessitated by the prior art and by the spirit of the appended claims.

What is claimed is:

1. In a turf cultivator for golf greens and the like, a frame, rollers supporting the frame at the front and rear thereof, a turf-splitting disc on the axis of the front roller for cutting a narrow slit in the turf, a very narrow plow shank depending from the frame intermediate the front and rear ends thereof to follow in the path of said disc, an inclined transverse blade secured to said shank and having its forward edge sharpened, and soil loosening teeth depending down from said blade at opposite sides of the shank, whereby the soil beneath the turf may be loosened while the turf itself is not impaired even temporarily by the operation.

2. In a turf cultivator for golf greens and the like, a frame, rollers supporting the frame at the front and rear thereof, a turf-splitting disc mounted centrally on the front roller for cutting

a narrow slit in the turf, a very narrow plow shank depending from the frame intermediate the front and rear ends thereof to follow in the path of said disc, an inclined transverse blade secured to said shank and having its lower edge sharpened, a container for fertilizer mounted on a support, a tube connecting said container with and discharging at the lower side of said blade, means for feeding the fertilizer into the tube, means for broadcasting the fertilizer radially from said discharge point, and soil loosening teeth mounted below said blade at opposite sides of the shank, whereby the soil beneath the turf may be loosened while the turf itself is not impaired even temporarily by the operation.

3. In a turf cultivator for golf greens and the like, a frame, rollers supporting the frame at the front and rear thereof, a turf-splitting disc associated with the front roller for cutting a narrow slit through the turf, a plow shank depending from the frame intermediate the front and rear ends thereof to follow in the path of said turf-splitting disc, said front roller and said plow shank being rigid against rotative movement about a vertical axis, an inclined transverse blade secured to said shank and having its forward edge sharpened to a knife edge, soil-loosening teeth mounted on said blade at opposite sides of the shank, means for supporting the frame above the front and rear rollers, and handles for guiding the cultivator extending upwardly and rearwardly from said frame.

4. In a turf cultivator for golf greens and the like, a frame, rollers supporting the frame at the front and rear thereof, a draft tongue extending forwardly of the frame for hitching the

5. In a turf cultivator to a draft vehicle, a turf-splitting disc mounted centrally on the front roller for cutting a narrow slit through the turf, an adjustable plow shank depending from the frame intermediate the front and rear ends thereof to follow in the path of said turf-splitting disc, an inclined transverse blade secured to said shank and having its forward edge sharpened to a knife edge, soil-loosening teeth mounted on the underside of said blade at opposite sides of the shank, means for supporting the frame above the front and rear rollers, handles for guiding the cultivator extending upwardly and rearwardly from said frame, and means on said frame for moving the turf-splitting disc and transverse blade into and out of operative position at will, whereby the soil beneath the turf may be loosened while the turf itself is not impaired even temporarily by the operation.

20 5. In a turf cultivator for golf greens and the like, a frame, rollers supporting the frame at the front and rear thereof, a very narrow plow shank depending from the frame intermediate the front and rear ends thereof, a turf-splitting means in advance of the said shank and aligned therewith so that the shank follows in the path of the said turf-splitting means, an inclined transverse blade secured to said shank and having its forward edge sharpened, and soil loosening teeth depending down from said blade at opposite sides of the shank whereby the soil beneath the turf may be loosened while the turf itself is not impaired even temporarily by the operation.
